UNITED STATES PATENT OFFICE.

HENRY S. NAGENGAST, OF GARDENVILLE, MARYLAND.

SHIELD AND DRIP-CATCHER FOR CANDLES.

SPECIFICATION forming part of Letters Patent No. 703,809, dated July 1, 1902.

Application filed February 27, 1902. Serial No. 95,870. (No model.)

To all whom it may concern:

Be it known that I, HENRY S. NAGENGAST, a citizen of the United States, residing at Gardenville, in the county of Baltimore and State 5 of Maryland, have invented certain new and useful Improvements in Shields and Drip-Catchers for Candles, of which the following is a specification.

This invention is an improved shield and 10 to drip-catcher for candles; and it consists in certain constructions and combinations of the parts hereinafter fully described and claimed, reference being had to the accompanying drawings, in which—

15 Figure 1 is a side elevation of the shield and drip-catcher. Fig. 2 is a similar view taken substantially at right angles to Fig. 1. Fig. 3 is a view of two candles, each provided with the shield and drip-catcher of the invention 20 and illustrating one particular use to which the invention may be put. Fig. 4 is a horizontal section taken on the line 4-4 of Fig. 3, but on a larger scale than the said Fig. 3.

Referring to the drawings, the letter *a* designates a sleeve or holder provided with a 25 transverse slot *a'*, and a clamping-finger *b* is pivoted to said sleeve and is provided with an inwardly-extending serrated end *b'*, which takes through said slot, the other end of said 30 clamp alongside of said sleeve being pressed outwardly by means of a spring *c*, as indicated in Fig. 2. A shield-supporting arm *d* is attached to said sleeve *a* and extends outwardly and upwardly from the sleeve and carries at 35 its upper end a suitable shield *e*, which in this instance is secured thereto by a nut and screw *e'*, and on the other side of said sleeve, diametrically opposite said arm *d*, a dish-shaped drip-catcher *f* is attached and extends 40 upwardly at an oblique angle therefrom, all as best shown in Fig. 1.

In operation the sleeve or holder *a* is slipped over the end of a candle and is clamped thereon, preferably at a point near the end to 45 be lighted, by means of the clamp. When the candle is lighted, it will be carried in a somewhat oblique position, with the drip-catcher *f* undermost, which latter will catch all the grease-drippings, and at the same time 50 the shield *e*, being over the flame, will prevent injury to anything.

It is to be understood that the shield *e* may be made of any suitable material, such as mica, in which case it will serve as a shield from the heat only of the flame, or it may be 55 made of translucent or opaque material to serve as a shade, or it may be made of a material having a burnished surface to serve as a reflector, and it is also to be understood that the invention is not limited to the construction shown, by which the shield is attached to its supporting-arm nor to the particular angular relation herein shown between the holder *a* and drop-catcher.

Fig. 3 of the drawings illustrates one use for 60 which my improved shield and drip-catcher may be employed. At a certain church festival the throats of communicants are blessed, and a portion of the ceremony consists in placing two lighted candles arranged in the 65 form of a cross, as shown in Fig. 3, in proximity to the communicant's throat. Articles of clothing and the hair have been frequently singed by the candle-flames in the observance 70 of this rite, and the vestments of the officiating priest have been injured by the drippings 75 from the candles; but it is manifest that the device of my invention obviates these unpleasant features. While this is one use for the device, it is obvious that the invention is 80 not limited to such use.

Having thus described my invention, what I claim as new, and desire to secure by Letters Patent, is—

1. A device for the purpose described, comprising a sleeve or holder adapted to be slipped over a candle and provided with a spring-pressed clamping-finger to secure it to the candle; a flame-shield carried by said holder; and a drip-catcher also carried by said 85 holder, as set forth.

2. A device for the purpose described, comprising a holder adapted to be secured on a candle; a shield-supporting arm attached to said holder at one side thereof; a shield secured to said arm; and a drip-catcher secured to said holder substantially diametrically opposite said arm, as set forth.

3. A device for the purpose described, comprising a holder adapted to be secured to a candle; a shield carried by said holder; and a drip-catcher also carried by said holder in 95 100

diametric relation to said shield and extending upwardly and outwardly therefrom in an oblique direction, as set forth.

4. A device for the purpose described, comprising a sleeve adapted to be slipped over a candle and provided with a clamping-finger to secure it to the candle; a supporting-arm attached to said holder and extending upwardly therefrom; a shield secured to the up-

per end of said arm; and a drip-catcher also attached to said sleeve, as set forth.

In testimony whereof I affix my signature in the presence of two witnesses.

HENRY S. NAGENGAST.
